(57) **CLAIM**

The ornamental design for a fire hydrant reflective disc, as shown and described.

DESCRIPTION

FIG. 1 is an environmental perspective view of a fire hydrant reflective disc showing our new design;

FIG. 2 is a front elevational, with the rear elevational view being unornamented, view thereof; and,

FIG. 3 is a top plan view, with the rear plan view and side elevational views being identical, thereof.

The broken line showing of the fire hydrant in FIG. 1 is for illustrative purposes only and forms no part of the claimed design.
